LIQUID DISPENSER FOR SURFACE
TREATING MACHINES

Axel Albert Forsberg, Stora Essingen, Sweden,
assignor to Aktiebolaget Elektrolux, Stockholm, Sweden, a corporation of Sweden

Application October 17, 1950, Serial No. 12,586
In Sweden June 19, 1950

Term of patent 14 years

(Cl. D9—2)

To all whom it may concern:

Be it known that I, Axel Albert Forsberg, a subject of the King of Sweden, residing at Stora Essingen, Sweden, have invented a new, original, and ornamental Design for a Liquid Dispenser for Surface Treating Machines, of which the following is a specification, reference being had to the accompanying drawing forming a part thereof.

In the drawing, Fig. 1 is a side perspective view of a liquid dispenser showing my design, and a surface treating machine which is illustrated in dotted lines for the purpose of showing the use of the liquid dispenser;

Fig. 2 is a rear perspective view thereof;

Fig. 3 is a top plan view of the liquid dispenser in which the chain thereof is illustrated in a coiled position;

Fig. 4 is an enlarged perspective view thereof to illustrate details more clearly;

Fig. 5 is a rear view thereof in elevation;

Fig. 6 is a side view thereof; and

Fig. 7 is a plan view thereof from below.

I claim:

The ornamental design for a liquid dispenser for surface treating machines, as shown and described.

AXEL ALBERT FORSBERG.
